Inventor:

Henry Wolcott
By Horatio E. Bellows

Attorney:

UNITED STATES PATENT OFFICE.

HENRY WOLCOTT, OF PROVIDENCE, RHODE ISLAND.

ORNAMENTAL CHAIN.

Application filed October 27, 1924. Serial No. 746,004.

To all whom it may concern:

Be it known that I, HENRY WOLCOTT, a citizen of the United States, residing at Providence, in the county of Providence and State of Rhode Island, have invented certain new and useful Improvements in Ornamental Chains, of which the following is a specification.

My invention relates to chains, straps, or bands for ornamental uses, such as in the construction of bracelets, armlets, belts, and structures of similar character.

The primary objects of my invention are to enable a facile and speedy removal or substitution of any link or unit of the chain or strap, for the purpose of repair or change of length; to insure against accidental unlocking or detachment of the inter-engaged parts of the units; to make possible construction of parts exclusively from blanks cut and bent from sheet metal; to avoid the necessity of fused connections; and to insure flexibility and strength.

To the enumerated ends essentially my invention consists in such parts and in such combinations of parts as fall within the scope of the appended claims.

In the accompanying drawings which form a part of this specification.

Figure 1 is an isometric view of a length of a chain, strap, or band embodying my invention,

Figure 2, an enlarged fragmentary front elevation of a portion of the same arranged in a plane and showing certain of the outer shells or tubes in longitudinal section,

Figure 3, a fragmentary plan view, partially in central longitudinal section of the same,

Figure 4, a fragmentary front elevation of the adjacent units with the parts in initial position for unlocking,

Figure 5, a like elevation of the same with the parts in unlocked position, and

Figures 6 and 7, detail views of a connecting member, and its carrier respectively.

Like reference characters indicate like parts throughout the views.

In the form of my invention herein illustrated the chain comprises a plurality of chain links or units 12, each of which consists of a tubular shell or casing 13 cut from a length of tubing, preferably rectangular in cross section, and, if desired, longitudinally curved as shown. The shell herein shown has a front and back wall 14 and 15 re-

spectively, and side walls 16. The center of the back wall is provided with a perforation 18.

A locking or carrier member 20, shown in Figure 7, is detachably mounted in each casing and consists of a resilient locking plate or base 21, integral with each of whose ends is a lug 22 comprising a narrow neck portion 23 disposed at substantially a right angle to the base, and a broader head portion 24 bent into a plane substantially parallel with the base. Intermediate the heads 24 and base 21 the neck 23 forms resultant cavities 25. The member 20 fits within its casing and is completely housed therein. The locking plate 21 rests against the shell wall 15 and is provided centrally with a rounded projection 26 indented in the material and which extends into the perforation 18 to lock the member 20 against movement.

Slidably mounted in each member 20 is an oblong link 29 provided with a central rectangular opening 30 constituting a frame having end bars 31 and side bars 32, and an inwardly directed ear 33 integral with the middle of one of the end bars, and lying in the plane of the frame, all as shown in Figure 6. The side bars 32 of the link 29 slides in the cavities 25 of one of the lugs 22 and projects into the next adjacent casing where its projecting portion, which may be referred to as its forward portion, surrounds the neck 23 of the rear lug in the second casing. An elliptic helical spring 34 is mounted in the opening 30 of each member 29 where it engages the ear 33. Its rear end abuts against the adjacent bar 31 of this member, and its forward end rests against the neck 23 of the forward lug 22, whereby the casings 13 are normally retained in contact with each other.

The described chain may be manually expanded and flexed as desired. To detach a link, a pin or other pointed implement is employed to press diagonally inward the projection 26 whereby the plate 21 yields and the projection 26 moves out of the perforation 18 and rests upon the inner face of the casing portion 15 which permits two of the adjacent units 12 to be separated an excessive distance, as shown in Figure 4. One of said adjacent units is then turned at an angle to the other so as to bring the frame 29 of the latter out of the cavities 25 of the engaging lug and, as shown in Figure 5, position the head 24 of the lug into a po-

sition to be removed from said frame, where-
upon the casings 13, which have during the
described operations been manually rear-
wardly pressed, are released. A similar op-
eration severs the opposite end of the ter-
minal unit 12. The severed lengths of the
chain may be reunited or another unit in-
serted by a reversal of the described opera-
tion.

10 I do not limit my invention to the exact
arrangement and combination of parts set
forth in this specification, nor do I confine
myself to the details of construction of any
of said parts illustrated in the accompany-
15 ing drawings.

I claim:

1. In an article of the type set forth, a
series of exterior hollow casings having open
ends and provided with perforations, resil-
ient carrier members mounted in the cas-
ings, projections on the carrier members
registering in the perforations to lock the
carriers, slideable links upon the carriers ex-

tending into adjacent shells adapted to en-
gage the carriers therein, and springs sup-
ported by the links engaging the carriers.

2. In an article of the type set forth, a
series of exterior hollow casings having open
ends and provided with perforations, car-
rier members comprising a resilient locking 30
plate adjacent the back of the casings, pro-
jections on the plates extending into the
perforations, forwardly directed necks upon
the ends of the plate, and inwardly directed
heads upon the necks adjacent the front of 35
the casings, open links slidably mounted in
the carrier embracing the necks upon the
forward ends of the carriers and the necks
of the rear ends of adjacent carriers, and
compression springs in the links engaging 40
the rear ends of the frames and the forward
necks on the carriers.

In testimony whereof I have affixed my
signature.

HENRY WOLCOTT.
